UNITED STATES PATENT OFFICE.

GUY P. THURBER, OF PITTSBURGH, PENNSYLVANIA, ASSIGNOR, BY MESNE ASSIGNMENTS, TO AUTOMATIC TRAIN CONTROL & SIGNAL COMPANY, OF PITTSBURGH, PENNSYLVANIA, A CORPORATION OF DELAWARE.

AUTOMATIC SIGNAL.

1,274,629.

Specification of Letters Patent.

Patented Aug. 6, 1918.

Application filed August 23, 1907. Serial No. 389,887.

To all whom it may concern:

Be it known that I, GUY P. THURBER, a citizen of the United States of America, residing at Pittsburgh, in the county of Allegheny and State of Pennsylvania, have invented certain new and useful Improvements in Automatic Signals, of which the following is a specification, reference being had therein to the accompanying drawing.

10 This invention relates to improvements in automatic signals, and the invention relates more particularly to a novel combination of devices for preventing railroad accidents and collisions.

15 The invention has for its object to provide a novel apparatus for controlling the air brakes in case of a broken rail, an open draw bridge, a misplaced switch, or any other mechanical or electrical defect in the 20 road bed or track of a railroad.

Another object of this invention is the provision of novel means for automatically stopping a train, should another train be in the preceding block or a designated section 25 of track.

My invention aims to provide novel devices for rendering visible and audible signals and in connection with these devices, I employ novel means for registering the 30 time of said signals and allowing a certain period of time for action upon the part of the engineer or party in control of the train. Failure upon the part of the engineer to bring his train to a stop is registered together with the time of day the signals were 35 given, and upon the expiration of a specified time, the train is immediately brought to a stop.

The signaling system comprising my improved automatic devices is particularly designed whereby it can be used in connection with and made a part of any signal system now in use by railroads. The system is intended to assist engineers of locomotives, 40 but should the engineer fail to see or hear a signal, the device which I employ, figuratively speaking, serves functionally as an "automaton engineer", immediately performing the duties of the engineer by setting 45 the brakes and preventing accidental injury or loss of human life and property in transit.

To this end, my automatic signal devices

tend to obviate accidents due to the many causes heretofore experienced in the operation of a railroad, and the many advantages 55 of the invention will be apparent, when the invention is fully understood, by those conversant with the maintenance of railroads.

The invention will be presently described in detail and reference will now be had to 60 the drawings forming a part of this specification, wherein,

Figure 1 is a diagrammatic view of the electrical connections and the mechanical elements of my invention, 65

Fig. 2 is a vertical sectional view of the dash-pot or piston valve,

Fig. 3 is a longitudinal sectional view of the throttle controlling cylinder,

Fig. 4 is a vertical sectional view of the 70 valve controlling cylinder,

Fig. 5 is a similar view of the whistle controlling cylinder or magnet valve.

Similar characters of reference indicate corresponding parts in the several views. 75

A main cab circuit is normally completed through the train and through the traffic tracks 1 and 2, the current passing from one truck 21 to another truck 22 through the rails aforesaid, and for this purpose the 80 wheels *w* of the truck 21 are insulated by means of the insulation material *w*¹, from the truck itself in a well-known manner. The track is divided into blocks by means of insulation 3 and 4 and normally there is 85 provided a path around this insulation from one track section to the other which when unruptured permits the cab circuit to be completed as the train passes over the insulation.

The main cab circuit is fed by the battery 28 and normally flows through conductor *d*¹, conductor *o*¹, armature 30, point *a*¹, relay 29, conductor 27, wheels *w*, thence through the track section and through the jumper circuit 95 when the train passes over the insulation in the track, by way of conductors 14 and 8, point 20, point *d*², conductor *d*⁴, battery *d*⁵, back to rail, through truck 22 to conductor *d*⁶, conductor *d*⁷, conductor *o*¹ and 100 back to battery 28. The cab battery 28 is preferably stronger than the battery *d*⁵.

This circuit normally holds the relay 29 energized and is normally complete when

the train is traveling along the track or when passing over the insulation in the track provided the path around the insulation has not been ruptured by the presence of another 5 train in an adjacent block or by some other means. When this circuit is ruptured relay 29 is deenergized and the armature 30 falls away from the point a^1 and since this main circuit flows both through the relay 29 and 10 through the armature 30 it is absolutely impossible for the relay 29 to pick up the said armature again except by the establishment of a bridge around the armature 30 in a manner to be later described.

15 Under the control of the relay 29 is a subsidiary cab circuit which is normally closed and which is fed by the battery 32. This subsidiary cab circuit is as follows: from battery 32, through conductor e^3 , through conductor e^4 , through the armature engaging the point 33, through conductor e^1 , conductor 20 31 , solenoid 34, conductor e^2 , through conductors d^1 and o^{10} to battery 32.

When the main cab circuit is broken and 25 the relay 29 is deenergized this auxiliary or subsidiary circuit is broken by the dropping of the armature away from the point 33 thereby deenergizing the solenoid 34 and admitting air from the reservoir 37 to the pipes 30 46 and 36 to whistle 38 and exhausting air from the timing switch k through pipe 70 and valve 35 to the atmosphere.

The relay 29 also holds a circuit normally closed through the signal b^x , which circuit 35 is as follows: from battery 28, through conductor d^1 , conductor o^4 , conductor z^3 , through armature engaging with contact point o , through conductor z , to signal b^x , through conductor z^1 , conductor d^1 , conductor 40 o^1 to battery 28. This signal b^x is a visual signal and is normally in position indicating safety so long as the energizing circuit remains unruptured. Upon the deenergization of the relay 29 the armature 45 connected to the conductor z^3 drops away from the contact point o and ruptures the circuit through the signal b^x thereby causing the signal to move to a position indicating danger.

50 When the relay 29 was deenergized the dropping of the armature 30 has ruptured the main circuit, but said armature coming in contact with the contact point 39 establishes a circuit through one side of the recording 55 clock 41 which may be traced as follows: from battery 28, through conductor d^1 , conductor o^4 , armature 30, contact point 39, conductor o^3 , to magnet x of the recording clock 41, to conductor o^2 , conductor d^1 , conductor 60 o^1 , and back to battery 28. This energizes the recording clock in a well known manner and causes the latter to record the time when the main circuit is ruptured, together with the time when the signal b^x is actuated and 65 the whistle 38 is sounded.

Thus the rupture of the main circuit gives both a visual and an audible signal to the engineer and records the time of the giving of such signals and by exhausting the air from the timing switch k sets means in operation which will eventually stop the train unless the main cab circuit is restored.

A predetermined period after the rupture of the main cab circuit, which period is governed by the length of time it takes the timing switch to drop, a second auxiliary or subsidiary circuit is ruptured. This second auxiliary or subsidiary circuit is a normally closed and charged circuit fed by the battery 32 and normally flows as follows: from battery 32, through conductor e^3 , conductor k^2 , to contact head p^{11} of the timing switch k through contact a^{12} , through conductor k^{10} , solenoid 44, conductor d^1 , conductor o^{10} , back to battery 32. This circuit normally holds 85 the solenoid 44 energized. Upon the exhaust of the air from the timing switch k and at the expiration of a predetermined period, the contact head p^{11} will have moved downward sufficiently to break the circuit at contact a^{12} thereby rupturing the circuit just described and deenergizing the solenoid 44. This permits air from the reservoir 37 to flow through pipes 46 and 45 to the cylinder 47, which in turn closes the throttle 48 and uncovers a port to the pipe 49 thereby admitting air to the cylinder 50 and exhausting air from the train line 53 to the atmosphere and thus applying the brakes.

The falling of the contact head p^{11} also 100 causes the contact a^{12} to establish a circuit which may be traced as follows: from battery 32, to conductor e^3 , conductor k^2 , contact head p^{11} , through contact a^{12} , conductor m^1 , through the magnet y of the recording 105 clock 41, through conductor o^2 , conductors d^1 and o^{10} , back to battery 32.

Thus the fact that the throttle has been closed and the brakes have been applied is likewise recorded by the recording clock.

If it is desired to restore the main cab circuit the engineman can push the button m^{20} thereby establishing a circuit as follows: (the train now being supposed to have passed beyond the insulation in the track 115 and to have an electrically continuous piece of track between the trucks 21 and 22) from battery 28, conductor d^1 , conductor o^4 , button m^{20} , relay 29, conductor 27, wheels w , track section, truck 22, conductors d^1 , d^1 and o^1 120 back to battery 28. This will energize the relay 29 and will cause it to pick up its armatures thereby restoring all circuits.

Reference will now be had to Fig. 5 of the drawings, wherein I have illustrated the 125 solenoid 34 and an air valve which can be termed "a whistle controlling valve." This valve controls the passage of air between the reservoir 37, the whistle 38, and a piston valve or dash-pot K. The air valve com- 130

- prises three parts, e^{11} , e^{21} and e^{31} . The part e^{11} conforms to the cap fitting upon the part e^{21} , said cap having a neck portion c^{21} carrying the solenoid 34. The neck portion c^{21} is provided with a bore c^{22} to accommodate a block c^{33} . The upper end of the block c^{33} is provided with a recess c^{44} having a valve seat c^{55} formed therein, in which the lower end of the solenoid rod e^{66} is adapted 5 to seat. Connecting with the lower end of this rod is a plunger c^{18} , having a valve end 35^x adapted to engage in the seat d^{11} formed in the upper end of the cavity d^{12} of the block c^{33} .
- 10 The neck portion c^{21} is provided with an exhaust port d^{31} communicating with a similar port d^{32} formed in the block c^{33} . The block c^{33} is also formed with a bypass d^{15} , the object of which will be presently described.
- 15 Between the parts e^{11} and e^{21} are arranged diaphragms e^{11} and e^5 , the cavity above the diaphragm e^{11} communicating with the bypass d^{15} and with a port e^6 , and a socket e^7 , 20 said socket receiving the end of a pipe 70, connecting with the dash-pot K.
- The part e^{21} of the valve is formed with a port f^1 to receive the end of a pipe 36. The port f^1 communicates with the cavity 25 d^{12} by a port f^2 , the port f^1 also communicates with the cavity f^3 , beneath the diaphragm e^5 , by a port f^4 . Connected to the diaphragm e^5 is a depending rod g^1 carrying a valve g^2 adapted to normally close the 30 opening g^{10} between the cavities g^3 and f^3 . The lower end of the part e^{21} is provided with a recess g^4 containing a plate g^5 having a valve seat g^6 formed therein. Adapted to engage in the valve seat g^6 is a valve h^1 35 controlled by a spring actuated rod h^2 , carried by a block h^3 screwed in the bottom of the part e^{21} . A diaphragm h^4 is arranged in the cavity g^3 to assist the movement of the depending rod g^1 . The cavity g^3 communicates with the recess g^4 by a port h^5 , and h^6 while another port h^{66} establishes communication between the atmosphere and the space below the diaphragm h^4 .
- The solenoid (34) is normally energized 40 drawing the solenoid rod e^{66} downward closing valve 35^x and opening valve 35 , closing valve g^2 and opening valve h^1 . Air now normally flows from the reservoir 37 through pipe 36 into opening f^1 45 through port f^2 into cavity d^{12} , thence past the open valve 35^x , through bypass d^{15} into cavity above diaphragm e^{21} , thence through port e^6 , through outlet e^7 , pipe 70 to dashpot or timing valve K by way of port y^{11} which 50 timing valve is thus normally sustained in its uppermost position by air pressure.
- When the solenoid 34 is deenergized the valve 35^x is opened, the valve 35^x is closed, the valve g^2 is opened and the valve h^1 is closed. This permits air to exhaust from the 55 timing valve K back through pipe 70, outlet e^7 , port e^6 , bypass d^{15} , past valve e^{55} , to ports d^{31} and d^{32} . This causes the piston v^{11} in the time switch to drop. At the same time air travels from inlet f^1 through port f^4 to cavity f^3 , past valve g^2 to cavity g^3 through ports h^6 and h^5 , to recess g^4 and thence through port i^1 to whistle 38.
- When the solenoid is used at the point 44 (Fig. 1), the outlets e^7 and i^1 are plugged up, 70 and the plug removed from the outlet between the ports h^6 and h^5 .
- In these circumstances when the solenoid is energized no air will flow to the cylinder 75 47, but when the solenoid is deenergized air will flow from inlet f^1 , through port f^4 to cavity f^3 , past valve g^2 , to recess g^4 , through port h^6 to outlet, through pipes 45 and 46 to cylinder 47 thereby closing the throttle.
- In Fig. 2 of the drawings, I have illustrated 80 a dash-pot consisting of a plurality of sections k^1 , k^{11} , and k^{111} , these sections being connected together by suitable sleeves. One end of the section k^{111} is provided with a stuffing-box n^{11} , through which operates a stem or piston rod o^{11} , carrying upon its upper end a head p^{11} , while intermediate its length the stem or piston rod is provided with a valve head r^{11} . This valve head r^{11} is provided with flap valves s^{21} and a valve 85 head is normally retained in engagement with the sleeve coupling t^{11} by a spring u^{11} mounted in the section k^{112} . The lower end of the stem or piston rod o^{11} is provided with a piston head v^{11} which is secured 90 thereon by a nut w^{11} . In this position the air has been released from under the piston head and the contact head p^{11} is in its lowered position.
- Secured upon the lower end of the section 95 k^{11} is a head x^{11} having the port y^{11} formed therein, heretofore referred to, this port communicating with the interior of the section k^{11} by a port z^{11} .
- The section k^1 carries an insulated washer 100 a^{11} and secured to said washer are spring contact arms a^{12} and a^{13} , one of said arms being of a greater length than the other. The lower ends of these arms are connected respectively to conductors m^1 and k^{10} (Fig. 110 115 1). The contact head p^{11} is further provided with insulating washer 13 and insulating bushing 13¹, and has the conductor k^2 connected to its metallic portion.
- When the piston or valve head p^{11} is sustained 120 in its uppermost position by air pressure, the contact a^{13} will engage the metallic head p^{11} while the contact a^{12} will be against the insulating bushing 13¹, thereby maintaining a circuit through the solenoid 44. 125 But when air is exhausted from underneath p^{11} , the head p^{11} will fall and the contact a^{13} will engage the insulating washer 13 while a^{12} will engage the metallic part of p^{11} , thereby rupturing the circuit through 44 and 130 0

establishing a circuit through the recording clock in the manner previously described.

- The type of air valve or throttle controlling cylinder which is employed is illustrated in Fig. 3 of the drawings, said valve comprising a cylinder 47^a having a head 4^a, and connecting with said cylinder is the air supply pipe 46. The cylinder 47^a is provided with a port 49 and in the cylinder is arranged a valve or piston head 48^a, which is normally retained in one end of the cylinder by the spring 6^a. As soon as the throttle 48 is closed, the valve in the cylinder uncovers the port 49, allowing air to pass into a brake valve cylinder 50, and closes the valve 51 thereof. This valve connects by a pipe 52 with the air reservoir 37 and with the main air supply pipe 53, which connects with the air brakes of a train.
- 20 The brake valve cylinder 50 and the air valve 51, illustrated in Fig. 4 of the drawing connects by the pipe 52, air tank 37 and pipe 53 to a conventional form of triple valve (not shown) to which the train line pipe is connected that controls the air brakes of a train. Within the cylinder 50 is a valve controlling piston rod 8^a carrying a piston head 9^a and valves 10^a and 11^a. The cylinder is provided with an exhaust port 12^a, and the valve 11^a is adapted to control a port 14^a formed in the valve 51. Normally, the valve 11^a is open so as to allow the excess pressure in the pipe 52 and tank 37 to overcome the pressure in the train line pipe.
- 30 When the piston rod 8^a moves downwardly, the air passes upwardly and exhausts through port 12^a. The piston 9^a is normally forced back to hold the valve 10^a in closed position by means of a coil spring 15^a encircling said piston rod.

Having now described my invention what I claim as new, is:

1. In a system of train control, fluid operated train controlling means normally inactive, an electrically controlled valve normally energized to prevent flow of fluid to hold the train controlling means inactive and adapted when deenergized to render the train controlling means active, a timing switch normally sustained by fluid pressure to maintain the electrically controlled valve energized and adapted when pressure is released to deenergize the electrically controlled valve, a cab circuit normally closed and charged, a valve under the control of the cab circuit for normally maintaining fluid pressure in the timing switch and adapted to release the fluid pressure in the timing switch when the cab circuit is ruptured.
2. In a system of train control, fluid operated train controlling means normally inactive, an electrically controlled valve normally energized to prevent flow of fluid to hold the train controlling means inactive

and adapted when deenergized to render the train controlling means active, a timing switch normally sustained by fluid pressure to maintain the electrically controlled valve energized and adapted when pressure is released to deenergize the electrically controlled valve, a cab circuit normally closed and charged, a valve under the control of the cab circuit for normally maintaining fluid pressure in the timing switch and adapted to release the fluid pressure in the timing switch when the cab circuit is ruptured, a recording time clock means for closing a circuit through the clock when the cab circuit is ruptured, and a second circuit adapted to be closed through said clock by the timing switch a predetermined period after pressure has been released in the same.

3. In a system of train control, an air reservoir, air actuated train controlling means normally inoperative, an electrically controlled fluid valve normally energized to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, a fluid valve under control of said circuit to normally permit flow of air from the reservoir to the timing switch and adapted when the cab circuit is ruptured to close communication between the air reservoir and timing switch and to release air pressure in the timing switch.

4. In a system of train control, an air reservoir, air actuated train controlling means normally inoperative, an electrically controlled fluid valve normally energized to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, an electrically controlled fluid valve normally maintained energized by the cab circuit to permit flow of air from the reservoir to the timing switch and adapted when the cab circuit is ruptured to release pressure in the timing switch.

5. In a system of train control, an air reservoir, air actuated train controlling means normally inoperative, an electrically controlled fluid valve normally energized

- to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, a fluid valve under control of said circuit to normally permit flow of air from the reservoir to the timing switch and adapted when the cab circuit is ruptured to close communication between the air reservoir and timing switch and to release air pressure in the timing switch, and a recording time clock adapted to record the actuation of the timing switch.
6. In a system of train control, an air reservoir, air actuated train controlling means normally inoperative, an electrically controlled fluid valve normally energized to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, a fluid valve under control of said circuit to normally permit flow of air from the reservoir to the timing switch and adapted when the cab circuit is ruptured to close communication between the air reservoir and timing switch and to release air pressure in the timing switch, a recording time clock, and connections thereto for recording the rupture of the cab circuit and the completion of actuation of the timing switch.
7. In a system of train control, an air reservoir, air actuated train controlling means normally inoperative, an electrically controlled fluid valve normally energized to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, an electrically controlled fluid valve normally maintained energized by the cab circuit to permit flow of air from the reservoir to the timing switch and adapted when the cab circuit is ruptured to release pressure in the timing switch, an audible signal connected with said last-mentioned electrically controlled fluid valve, adapted to be sounded when said valve is deenergized, and a recording time clock adapted to record the time of sounding the audible signal and the time of completion of movement of the timing switch.
8. In a system of train control, an air reservoir, air actuated train controlling means normally inoperative, an electrically controlled fluid valve normally energized to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, an electrically controlled fluid valve normally maintained energized by the cab circuit to permit flow of air from the reservoir to the timing switch and adapted when the cab circuit is ruptured to release pressure in the timing switch, an audible signal connected with said last-mentioned electrically controlled fluid valve, adapted to be sounded when said valve is deenergized, and a recording time clock adapted to record the time of sounding the audible signal and the time of completion of movement of the timing switch.
9. In a system of train control, an air reservoir, air actuated train controlling means normally inoperative, an electrically controlled fluid valve normally energized to prevent flow of air from the reservoir to the train controlling means and adapted when deenergized to admit air from the reservoir to the train controlling means, a timing switch normally in communication with the air reservoir and sustained by air pressure to normally maintain the electrically controlled valve energized and adapted when air pressure is released to deenergize the electrically controlled valve, a normally closed and charged cab circuit, an electrically controlled fluid valve normally maintained energized by the cab circuit to permit flow of air from the reservoir to the timing switch and adapted when the cab circuit is ruptured to release pressure in the timing switch, an audible signal connected with said last-mentioned electrically controlled fluid valve, adapted to be sounded when said valve is deenergized, and a visual signal adapted to be operated upon the rupture of the cab circuit.
10. In a train controlling system, a main cab circuit, a subsidiary cab circuit under control of the same, a magnet valve in said subsidiary circuit, a timing switch connected with the magnet valve and controlled thereby, train controlling means, a circuit controlled by the timing switch, and a second magnet valve located in the circuit con-

- trolled by the timing switch, the said second magnet valve controlling the train controlling means and arranged to normally maintain the train controlling means in active.
11. In a train controlling system, a cab circuit, a magnet valve in said cab circuit, a timing switch connected with the magnet valve and controlled thereby, a circuit controlled by the timing switch, train controlling means, and a second magnet valve located in the circuit controlled by the timing switch, the said second magnet valve controlling the train controlling means and arranged to normally maintain the train controlling means inactive.
12. In a train controlling system, a normally closed and charged cab circuit, a magnet valve in said cab circuit, a timing switch connected with and controlled by the magnet valve, a circuit controlled by the timing switch, train controlling means, and a second magnet valve located in the circuit controlled by the timing switch, the said second magnet valve controlling the train controlling means and arranged to normally maintain the train controlling means inactive.
13. In a train controlling system, a normally closed and charged cab circuit, a magnet valve in said cab circuit, a timing switch connected with and controlled by the magnet valve, a normally closed and charged circuit controlled by the timing switch, train controlling means, and a second magnet valve exercising control over the train controlling means, said second magnet valve being located in the circuit controlled by the timing switch and normally energized thereby to maintain the train controlling means inactive.
14. In a train controlling system, a normally closed and charged cab circuit, a timing switch, a magnet valve located in the cab circuit adapted upon the rupture of said circuit to render the timing switch operative, train controlling means, a circuit controlled by the timing switch, a second magnet valve in the circuit controlled by the timing switch connected with the train controlling means for normally maintaining the train controlling means inactive, a visual signal, and a circuit for actuating the same upon the rupture of the cab circuit.
15. In a train controlling system, a normally closed and charged cab circuit, a timing switch, a magnet valve located in the cab circuit adapted upon the rupture of said circuit to render the timing switch operative, train controlling means, a circuit controlled by the magnet valve, a circuit controlled by the timing switch, a second magnet valve in the circuit controlled by the timing switch for normally maintaining the train controlling means inactive, a recording time clock, and a circuit for sending a recording impulse thereto upon the rupture of the cab circuit, a visual signal, and a circuit for actuating the same upon the rupture of the cab circuit.
16. In a train controlling system, a normally closed and charged cab circuit, a timing switch, a magnet valve located in the cab circuit adapted upon the rupture of said circuit to render the timing switch operative, train controlling means, a circuit controlled by the timing switch, a second magnet valve in the circuit controlled by the timing switch for normally maintaining the train controlling means inactive, a recording time clock, a circuit for sending a recording impulse thereto upon the rupture of the cab circuit, a visual signal, and a circuit for actuating the same upon the rupture of the cab circuit.
17. In a train controlling system, a normally closed and charged cab circuit, a timing switch, a magnet valve located in the cab circuit adapted upon the rupture of said circuit to render the timing switch operative, train controlling means, a circuit controlled by the timing switch, a second magnet valve in the circuit controlled by the timing switch for normally maintaining the train controlling means inactive, a recording time clock, a circuit for sending a recording impulse thereto upon the rupture of the cab circuit, and a circuit for sending a second recording impulse to the recording clock upon completion of the actuation of the timing switch.
18. In a train controlling system, a normally closed and charged cab circuit, a timing switch, a magnet valve located in the cab circuit adapted upon the rupture of said circuit to render the timing switch operative, train controlling means, a circuit controlled by the timing switch, a second magnet valve in the circuit controlled by the timing switch for normally maintaining the train controlling means inactive, a recording time clock, a circuit for sending a recording impulse thereto upon the rupture of the cab circuit, a circuit for sending a second recording impulse to the recording clock upon completion of the actuation of the timing switch, a visual signal, and a circuit for actuating the same upon the rupture of the cab circuit.
19. In a train controlling system, a cab circuit, a magnet valve in said cab circuit, an audible signal adapted to be actuated by said magnet valve, a timing switch also controlled by the magnet valve, a circuit controlled by the timing switch, train controlling means, and a second magnet valve located in the circuit controlled by the timing switch, said second magnet valve controlling the train controlling means and arranged to normally maintain the train controlling means inactive.
20. In a train controlling system, a normally closed and charged cab circuit, a mag-

- net valve in said cab circuit, a timing switch connected with the magnet valve and normally held inactive so long as said magnet valve is energized, an audible signal also controlled by the magnet valve and held inactive while said valve is energized, a circuit controlled by the timing switch, train controlling means, and a second magnet valve located in the circuit controlled by the timing switch and connected with the train controlling means for normally maintaining the train controlling means inactive. 21. In a train controlling system, a normally closed and charged cab circuit, a magnet valve in said cab circuit, a timing switch connected with the magnet valve and normally held inactive so long as said magnet valve is energized, an audible signal also controlled by the magnet valve and held inactive while said valve is energized, a circuit controlled by the timing switch, train controlling means, a second magnet valve located in the circuit controlled by the timing switch and connected with the train controlling means for normally maintaining the train controlling means inactive, a visual signal, and a circuit for actuating the same upon the rupture of the cab circuit. 22. In a system of train control, train controlling means normally inactive, a switch controlled by fluid pressure to normally hold the train controlling means inactive, and a normally closed charged circuit and means controlled thereby for normally maintaining fluid pressure in said switch, whereby the rupture of the circuit or the breaking of the fluid pressure will cause the train controlling means to be operated. 23. In a system of train control, train controlling means normally inactive, an electrically controlled valve adapted when energized to prevent flow of fluid to the train controlling means, a switch controlled by fluid pressure to normally hold the electrically controlled valve energized and adapted to deenergize said valve when the fluid pressure is broken, and a normally closed charged circuit and means controlled thereby for normally maintaining fluid pressure in said switch and adapted when ruptured to break the fluid pressure in the switch. 24. In a system of train control, train controlling means normally inactive, an electrically controlled valve adapted when energized to prevent flow of fluid to the train controlling means, a switch controlled by fluid pressure to normally hold the electrically controlled valve energized and adapted to deenergize said valve when the fluid pressure is broken, and a second electrically controlled valve adapted when energized to maintain fluid pressure in said switch and when deenergized to break the fluid pressure in said switch. 25. In a system of train control, train controlling means normally inactive, an electrically controlled device for maintaining the train controlling means inactive, a switch controlled by fluid under pressure, connections between said switch and the electrically controlled device, and a normally closed charged electric circuit controlling the fluid. 26. In a train controlling system, a main cab circuit, a subsidiary cab circuit under control of the same, a magnet valve in said subsidiary circuit, a timing switch connected with the magnet valve and controlled thereby, train controlling means, a circuit controlled by the timing switch, a second magnet valve controlling the train controlling means, and arranged to normally maintain the train controlling means inactive. 27. In a train controlling system, a cab circuit, a magnet valve in said cab circuit, a timing switch connected with the magnet valve, and controlled thereby, a circuit controlled by the timing switch, train controlling means, and a second magnet valve controlling the train controlling means, and arranged to normally maintain the train controlling means inactive. 28. In a train controlling system, a normally closed and charged cab circuit, a magnet valve in said cab circuit, a timing switch connected with and controlled by the magnet valve, a circuit controlled by the timing switch, train controlling means, and a second magnet valve controlling the train controlling means, and arranged to normally maintain the train controlling means inactive. 29. In a train controlling system, a normally closed and charged cab circuit, a magnet valve in said circuit, a timing switch connected with and controlled by the magnet valve, a normally closed and charged circuit controlled by the timing switch, train controlling means, and a second magnet valve exercising control over the train controlling means. 30. In a train controlling system, a normally closed and charged cab circuit, a timing switch, a magnet valve located in the cab circuit adapted upon the rupture of said circuit to render the timing switch operative, train controlling means, a circuit controlled by the timing switch, a second magnet valve connected with the train controlling means for normally maintaining the train controlling means inactive, a visual signal, and a circuit for actuating the same upon the rupture of the cab circuit. 31. In a train controlling system, a cab circuit, a magnet valve in said cab circuit, an audible signal adapted to be actuated by said magnet valve, a timing switch, also controlled by the magnet valve, a circuit controlled by the timing switch, train controlling means, and a second magnet valve controlling the train controlling means, and ar- 100 105 110 115 120 125 130

ranged to normally maintain the train controlling means inactive.

32. In a train controlling system, a normally closed and charged cab circuit, a magnet valve in said cab circuit, a timing switch connected with the magnet valve and normally held inactive so long as said magnet valve is energized, an audible signal also controlled by the magnet valve and held inactive while said valve is energized, a circuit controlled by the timing switch, train controlling means, and a second magnet valve connected with the train controlling means, for normally maintaining the train controlling means inactive.

33. In a train controlling system, a normally closed and charged cab circuit, a magnet valve in said cab circuit, a timing switch connected with the magnet valve, normally held inactive so long as said magnet valve is energized, an audible signal also controlled by the magnet valve and held inactive while said valve is energized, a circuit controlled by the timing switch, train controlling means, and a second magnet valve connected with the train controlling means for normally maintaining the train controlling means inactive, a visual signal and a circuit for actuating the same upon the rupture of the cab circuit.

34. In a train controlling system, a cab circuit, a magnet valve in said cab circuit, an audible signal adapted to be actuated by said magnet valve, a timing switch also controlled by the magnet valve, and a train controlling means under control of the magnet valve and arranged to be inoperative so long as the valve is energized.

35. A system of train control comprising: an air brake system, a closed electric circuit and means therein for normally holding the air brake system inoperative, and fluid pressure means connected to the air brake system for normally holding the electric circuit complete.

36. A system of train control comprising: an air brake system, a closed electric circuit and means therein for normally holding the air brake system inoperative, fluid pressure means connected to the air brake system for normally holding the electric circuit complete, and a closed electric circuit for normally holding the fluid pressure means in its circuit closing position.

37. A system of train control comprising: train controlling means, a normally energized magnet valve normally holding said train controlling means inoperative, a circuit for said magnet valve, a fluid actuated circuit breaker for normally holding said circuit complete, and a magnet valve normally energized and which when energized holds the fluid actuated circuit breaker in its circuit closing position.

38. A system of train control comprising:

train controlling means, a normally energized magnet valve normally holding said train controlling means inoperative, a circuit for said magnet valve, a fluid actuated circuit breaker for normally holding said circuit complete, and a normally energized magnet valve normally admitting fluid to the circuit breaker to normally hold it in its circuit closing position.

39. In a system of train control, train controlling means, a normally closed electric circuit for normally holding said train controlling means inoperative, a fluid pressure circuit breaker, and a magnet valve normally energized for normally admitting fluid pressure to the circuit breaker to normally hold it in its circuit closing position, and which when deenergized exhausts fluid pressure from the circuit breaker to cause it to rupture the circuit.

40. In a system of train control, train controlling means, a normally closed electric circuit for normally holding said train controlling means inoperative, a fluid pressure circuit breaker, a signaling device operated by fluid pressure, and a magnet valve normally energized for normally admitting fluid pressure to the circuit breaker to normally hold it in its circuit closing position, and for normally excluding fluid pressure from the signaling device, and which when deenergized exhausts fluid pressure from the circuit breaker to cause it to rupture the circuit, and admits fluid pressure to the signaling device.

41. In a train controlling system, a throttle, a fluid pressure actuated throttle closing valve, a normally energized magnet valve which when deenergized admits fluid pressure to the throttle closing valve, a brake valve interposed in the train line and actuated by the throttle closing valve, a circuit for the magnet valve, and a fluid actuated circuit breaker for normally holding said circuit closed.

42. In a train controlling system, a throttle, a fluid pressure actuated throttle closing valve, a normally energized magnet valve which when deenergized admits fluid pressure to the throttle closing valve, a brake valve interposed in the train line and actuated by the throttle closing valve, a circuit for the magnet valve, a fluid actuated timing switch for normally holding said circuit closed, and means for causing said timing switch to rupture the circuit.

43. In a train controlling system, a throttle, a fluid pressure actuated throttle closing valve, a normally energized magnet valve which when deenergized admits fluid pressure to the throttle closing valve, a brake valve interposed in the train line and actuated by the throttle closing valve, a circuit for the magnet valve, a fluid actuated timing switch for normally holding said circuit closed.

cuit closed, and another magnet valve which when deenergized causes said timing switch to rupture the circuit.

44. In a train controlling system, a throttle, a fluid pressure actuated throttle closing valve, a normally energized magnet valve which when deenergized admits fluid pressure to the throttle closing valve, a brake valve interposed in the train line and actuated by the throttle closing valve, a circuit for the magnet valve, a fluid actuated circuit breaker for normally holding said circuit closed, and another magnet valve which when deenergized causes said circuit breaker to rupture the circuit.
45. A train controlling system comprising-

ing: an air brake system, a normally closed electric circuit normally holding said system inoperative, a fluid actuated circuit breaker normally receiving air from the air brake system to hold the circuit closed, and an electrically actuated valve which when deenergized causes fluid to exhaust from the circuit breaker so that the latter will rupture the normally closed circuit.

In testimony whereof I affix my signature in the presence of two witnesses.

GUY P. THURBER.
